NECKTIE

Filed June 8, 1929

UNITED STATES PATENT OFFICE

JOSEPH M. I. MARIN AND DAISY S. RUBENS, OF JERSEY CITY, NEW JERSEY

NECKTIE

Application filed June 8, 1929. Serial No. 369,313.

This invention relates to neckties, and has reference to a retainer or support for the device whereby the necktie may be retained in place with respect to a laydown collar without training the neckband portion of the tie between the folds of the collar.

Another very important object of the invention is the provision of a retainer of the class described which will greatly enhance the appearance of the tie, will retain the tie in a neat position with respect to the collar, will permit of ease and rapidity in placing the tie in position with respect to the collar when the former is to be worn, and which will also aid in the prolongation of the life of the necktie.

A still further and salient feature of this invention is the provision of a device of this nature, which is simple in construction, can be easily applied either to the conventional tie whether it be of the four in hand or bow type, said device being also capable of use in conjunction with made up ties, will present a neat attractive appearance, practicable, efficient and otherwise well adapted for the purpose designed.

Other objects and advantages of the invention will become apparent during a study of the following description, taken in connection with the accompanying drawings, wherein:

Figure 1 is a front view of a tie or scarf showing the application of the invention thereto.

Figure 2 is a rear view thereof, and illustrating the means whereby the tie is held in proper position through the cooperation of the collar button.

Figure 3 is a diagrammatic or plan view of a retainer constructed in accordance with this invention, and at the first stage of its construction.

Figure 4 is an elevation of the retainer, illustrating an advance stage of construction.

Figure 5 is a view similar to Figure 4 showing the retainer encased or covered by suitable material, the material conforming to the material of the scarf or tie, said retainer being at its final stage of construction prior to its association with the tie or scarf.

Figure 6 is a side elevation of a conventional collar button, suitable for use with the type of cooperative fastening means of the tie to be associated therewith, in accordance with the preferred embodiment of the invention.

With reference more in detail to the drawings, attention is first directed to Figures 3, 4, and 5 wherein we will follow the different stages incidental to the construction of the improved retainer. As illustrated in Figure 3 the retainer is preferably formed from an elongated piece of fabric, of any material of suitable stiffness, but preferably of buckram as indicated at 5, since in practice it has been found that buckram possesses the desired resilient stiffness desired in retainers used in this manner. As illustrated then the retainer 5 formed of buckram is so cut and shaped from the material as to be of substantially triangular formation. The elongated edge 6 and the edges 7-7 at opposite ends of the retainer, terminate in the squared ends 8. It is to be noted that along its marginal edge the retainer is stitched as at 9, thus enhancing the stiffening quality of the material forming the said retainer. At its widest point, that is at a point intermediate its ends the retainer is folded inwardly and over upon itself as at 11 so as to assume a substantially V-shaped configuration embodying the outwardly diverging arms 12-12. Having thus attained the simulation of a V, the same as its outer edge and at the apex thereof has a portion of the material cut therefrom so as to provide the straight edged portion 13. The retainer 5 is covered with material from which the tie is made to provide a pocket or sheath 14 for the retainer as clearly illustrated in Figure 5.

Attention is now directed to Figures 1 and 2, wherein is illustrated a tie or scarf designated generally by the reference character A. The scarf or tie A has its knot portion disposed about the retainer at the apex thereof and knotted in a suitable manner as at 15 so as to permit the apron portions 16 and 17, respectively, of the tie to depend from the retainer in a suitable manner and in simulation of an ordinary tie knotted about the neck.

However, to maintain the tie suitably positioned upon the retainer it is preferable to stitch the knot portions of the tie rearwardly of the knot as at 18. For the sake of convenience to the wearer it is also preferable to shorten the length of the apron portion 16 of the tie A either after or prior to the positioning of the tie upon the retainer, and then stitching or otherwise securing the depending extremity of the said apron 16 to the apron 17 as at 19. It is of course to be understood that the apron portion 16 is that part of the tie which is hidden behind the front apron 17, thus this manner of assembly just mentioned will present no undesirable feature to the tie as would render it undesirable for wear, but rather would prove an added advantage, since such permits that merely one apron extending in front of the wearer presenting a natty and dressy appearance, which is not always the case when the rear apron of the tie hangs loosely as in the ordinary manner. To the rear of the knot 15 of the tie or scarf A, and especially in adapting the invention to a ready made neck tie there is provided an auxiliary fastening element fixed to the knot by stitching or in any other preferred or desired manner. This fastening element is in the nature of a socket and is designated generally by the reference character 20, (see Figure 2). Thus it will be seen that the socket 20 is exposed to the back of the tie and the said socket is adapted to receive the ball-like head 21 of a conventional collar button 22.

In practice then it will be seen that the tie associated with the retainer as herein described may be conveniently and easily worn with any type of lay-down collar, the wings or legs 12 of the retainer will extend beneath the usual flap of a collar (not shown), so as to position the tie in proper relation to the collar and permit of the socket 20 to be pressed onto the head 21 of the collar button 22 whereby obviously the knot 15 of the tie will remain in its proper position while the tie is being worn, thus ever presenting a neat and attractive appearance.

Obviously when the socket and collar button are engaged as before mentioned, the tie is secure against any tendency to displacement, except when the same is pulled forwardly or outwardly, such occurring in most instances when intentional by the wearer for removing the necktie.

From the foregoing then it will be seen that a tie embodying the features of construction as illustrated in the present invention, when worn in position will be maintained therein and that such is not likely to become soiled which is often the case when the tie is disposed about the collar and knotted in position at each wearing, the knot often slipping and becoming disarranged, thus necessitating the handling of the tie for repositioning the same in its proper place, which

often causes the soiling of the tie by one's hands, especially this being the case in warm weather.

Even though we have shown the preferred embodiment of my invention, it is to be understood that the same is susceptible to certain changes fully comprehended by the spirit of the invention as herein described, and the scope of the appended claim.

Having thus described the invention, what we claim as new and desire to secure by Letters Patent is:

As a new article of manufacture, a necktie retainer formed from a single blank of resilient material having an intermediate portion folded upon itself to provide a substantial V—including a pair of diverging arm portions, the folded portions of said blank being cut longitudinally adjacent one edge of the blank whereby to provide a substantially truncated apex for said V, said arm portions of said retainer adapted to be disposed beneath the wings of a collar, and the truncated apex of said member adapted to accommodate the knotted portion of a necktie for retaining the latter in a supported position from said retainer.

In testimony whereof we affix our signatures.

JOSEPH M. I. MARIN. 95
DAISY S. RUBENS.
